UNITED STATES PATENT OFFICE.

PETER J. WESOLOWSKI, OF DETROIT, MICHIGAN.

CAN-HEAD-CUTTING MACHINE.

1,100,802.

Specification of Letters Patent. Patented June 23, 1914.

Application filed February 2, 1910. Serial No. 541,608.

To all whom it may concern:

Be it known that I, PETER J. WESOLOWSKI, a citizen of the United States of America, residing at Detroit, in the county of Wayne and State of Michigan, have invented certain new and useful Improvements in Can-Head-Cutting Machines, of which the following is a specification, reference being had therein to the accompanying drawings.

10 The invention relates particularly to can opening mechanism, and consists in the novel and simple construction of a machine for this purpose, in the peculiar arrangement and combination of its parts, and in various 15 details of construction as will be more fully hereinafter set forth and claimed.

In the drawings,—Figure 1 is a view, partly in side elevation and partly in section, of a can opener embodying my invention; 20 Figs. 2 and 3 are enlarged detached perspective views of parts of the mechanism; Fig. 4 is a perspective view of the top member or plate detached; and Fig. 5 is a detached perspective view of the can support, with the 25 top member or plate removed, illustrating the construction of the clamping mechanism.

In the drawings thus briefly described, A represents a base section, upon which the can to be opened is mounted, and B an upright 30 or standard at one side thereof and preferably connected thereto, the parts being usually constructed to form a single casting. The base as shown has its top surface recessed, as at a, and vertically, as at b, the 35 two recesses communicating (as shown in Fig. 1) and adjoining the horizontal recess with a bore or socket c.

C represents the can support, mounted upon the base for rotary movement. It is 40 loosely sleeved upon a rotary actuating member such as a stub shaft D that fits within the socket c, and above the socket within the recess a it carries a gear wheel E. The support comprises a rotatable supporting 45 member F loose upon the shaft D and resting on the base, and with a cover section G, between which parts are arranged the sliding clamping jaws H and I that serve to grip and hold the can. The jaws, as shown, 50 are provided with shank portions d, each longitudinally slotted, as at e, and the plate F of the support carries studs f and g that engage the slots described, and also raised 55 portions h at opposite sides that extend flush with the jaw shanks and serve as supports for the cover section G, the latter being se-

cured in place by suitable screws or bolts j. The cover section last referred to has its ends recessed, as at i, to receive the clamping jaws, and to permit the latter to be drawn together inwardly beyond the periphery of the support a sufficient distance to properly grip the can. For operating the jaws, a pinion J is provided fixed upon the upper end of the shaft D in a position to engage rack 60 teeth K upon the meeting sides of the jaw shanks, as illustrated, and a crank L for actuating the pinion. This crank is secured to a shaft M journaled in the base, which carries at its inner end a gear O meshing 65 with the gear E previously described, fixed upon the stub shaft D.

The standard B at its upper end is formed with a reduced section P, the extremity of which is screw-threaded, as at m. Swiveled 70 upon this reduced portion is a sleeve Q, and projecting laterally from this sleeve and pivoted thereto for vertical movement or adjustment is an arm R carrying at its extremity a cutter S, the arm being of sufficient 75 length to position the cutter over the can support to properly engage the can head.

In construction, the cutter comprises a head T, the usual cutter blade U, and a shank V having a screw-threaded engagement with the head and being spaced from the knife a sufficient distance to permit of its use as a guard or guide member for the cutter, this portion being adapted to contact with the body of the can and thus guide the 80 cutter in the opening of the head.

The arm connecting the cutter to the standard is preferably composed of parallel links V' and W, pivoted at their ends to the cutter head and to the sleeve, this construction 85 producing a parallelogram movement of the cutter, so that in raising or lowering the same in relation to the base in opening cans of different height the cutter will always be maintained in its proper vertical 90 position.

In the operation of the mechanism, the can to be opened is first placed upon its support, the jaws having previously been properly opened to receive the can base. Upon 105 rotation of the crank, the jaws first operate and clamp the can, and upon subsequent rotation the can is revolved. The cutter is then raised or lowered the required distance to engage the can head, and is shifted in a 110 horizontal plane through its swiveled connection with the standard to bring the knife

to the proper cutting position with the guide V adjoining the can body. The knife is then driven downwardly into the can, and the latter rotated, and the can head is removed.

5 In practice, I find it desirable to provide means for holding the cutter downwardly into engagement with the can during the operation of cutting, and for this purpose I 10 have provided a spring X that serves normally to depress the cutter. This spring is usually arranged within a fork Y formed upon the link end adjoining the sleeve, with its opposite ends engaging respectively the 15 sleeve and the arm or link. Two of these springs may be employed, if desired. It is also desirable to hold the arm in different positions in its horizontal swinging movement. I therefore employ a coil spring A' 20 encircling the reduced section P of the standard, bearing at its upper end against a removable cap B' and at its lower end against an annular flange C' carried by the sleeve. As thus constructed, after the arm has been 25 properly positioned or adjusted, it will maintain the position without the necessity of being held by the operator.

From the foregoing description of the mechanism it will be obvious that both the 30 gripping of the can on its support and the rotation of the can is effected through the agency of a single controlling member or operating device, which not only simplifies the construction of the machine but also its 35 operation. Furthermore, the cutter is removable from its supporting head, and can be readily removed either for repair or replacement.

What I claim as my invention is,—

40 1. In a can opener, the combination with a rotatable support, of clamping jaws for the can mounted upon the support for movement transversely thereof, but secured thereto against relative rotation, said jaws being 45 provided with racks, a vertical shaft upon which said support is loosely mounted, a pinion fixed to said shaft engaging said racks, a rotatable actuating member, and a direct connection between said actuating member 50 and said shaft independent of said pinion and racks.

2. In a can opener, the combination with a rotatable support, of clamping jaws for the can mounted upon the upper face of the 55 support for movement transversely of the

latter but secured thereto against relative rotation, said jaws being provided with longitudinal racks on the sides thereof, a vertical shaft upon which said support is loosely mounted, a pinion fixed to said shaft 60 above the support and engaging said racks, a rotatable actuating member, and a direct connection between said actuating member and said shaft independent of said pinion and rack.

3. In a can opener, the combination with a base having a recess therein, a vertical rotatable shaft having a bearing in said recess, a pinion carried by said shaft positioned beneath the upper face of said base, 70 a gear meshing with said pinion, a handle for rotating said gear, a rotatable support resting on the base and loosely sleeved in said rotatable shaft, clamping jaws positioned in said support having longitudinal 75 slots therein, studs carried by said support engaging said slots and permitting transverse movement of said jaws relative to said support, a cover section positioned above said jaws upon which the can to be opened 80 is placed, said support having a raised portion for supporting said cover, said jaws having teeth adapted to engage said pinion for clamping said jaws upon the initial turning of the handle, the connection between 85 the studs and the slots in said jaws preventing the rotation of said jaws relative to said support and co-operating to rotate the support in the clamped position of said jaws.

4. In a can opener, the combination with 90 a base, of a rotatable shaft mounted therein, a supporting member mounted on said base and loosely sleeved on said shaft, pinions fixedly secured to said shaft above and below said supporting member jaws positioned 95 above said supporting member on opposite sides of the upper pinion and having teeth engaging therewith, slots in the shank portions of said jaws, and studs carried by said supporting member permitting transverse 100 movement of said jaws but preventing rotary movement thereof relative to said supporting member, and means for rotating the lower pinion.

In testimony whereof I affix my signature 105 in presence of two witnesses.

PETER J. WESOLOWSKI.
